CLAIM

(21) Appl. No.: **29/442,442**

I claim the ornamental design for a hair iron heating plate for
straightening and curling hair, as shown and described.

(22) Filed: **Mar. 4, 2013**

DESCRIPTION

(51) LOC (10) Cl. **28-03**

FIG. 1 is a perspective view showing my new design.

(52) U.S. Cl.

FIG. 2 is a front view thereof.

USPC **D28/35**

FIG. 3 is a right end view thereof.

(58) **Field of Classification Search**

FIG. 4 is a left end view thereof.

USPC 219/222-226; 132/222, 223-272;
D28/35, 37-38, 40

FIG. 5 is a top view thereof.

See application file for complete search history.

FIG. 6 is a bottom view thereof.

(56) **References Cited**

FIG. 7 is a perspective view of the second embodiment of my
new design.

U.S. PATENT DOCUMENTS

FIG. 8 is a front view of FIG. 7 where the upper and lower
plates are pressed in contact with one another; and,

6,627,852 B1 * 9/2003 Savone 219/225
D606,251 S * 12/2009 Leung D28/35
